DESIGN FOR A CASSEROLE OR SIMILAR ARTICLE

Clarence Karstadt, Glen Ellyn, Ill., assignor to Sears, Roebuck and Co., Chicago, Ill., a corporation of New York

Application June 1, 1942, Serial No. 107,064

Term of patent 14 years

To all whom it may concern:

Be it known that I, Clarence Karstadt, a citizen of the United States of America, residing at Glen Ellyn, in the county of Du Page and State of Illinois, have invented a new, original, and ornamental Design for a Casserole or Similar Article, of which the following is a specification, reference being had to the accompanying drawing, forming a part thereof.

Fig. 1 is a top plan view of a casserole or similar article embodying my new design;

Fig. 2 is a side elevational view of the article
shown in Fig. 1;

Fig. 3 is a plan view of the inside of the lid
portion of the same;

Fig. 4 is a plan view of the bottom portion of the article shown in Figs. 1 and 2; and

Figs. 5 and 6 are fragmentary sectional views taken respectively along the lines 5—5 and 6—6
of Fig. 1 and in the direction of the arrows.

I claim:

The ornamental design for a casserole or similar article, as shown.

CLARENCE KARSTADT.
